(57) **CLAIM**

The ornamental design for a pour over beverage maker, as shown and described.

DESCRIPTION

FIG. 1 is a perspective view of a pour over beverage maker showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The dash-dash broken lines in the drawings depict portions of the pour over beverage maker that form no part of the claimed design. The dash-dot broken lines in drawings define the bounds of the claimed design and form no part thereof.
